UNITED STATES PATENT OFFICE.

WILLIAM F. LAUTENSCHLAGER, OF CINCINNATI, OHIO.

METHOD OF CEMENTING THE MARGINS OF FLEXIBLE MATERIAL.

1,223,404.

Specification of Letters Patent. Patented Apr. 24, 1917.

Application filed August 19, 1915. Serial No. 46,269.

To all whom it may concern:

Be it known that I, WILLIAM F. LAUTENSCHLAGER, a citizen of the United States, residing at Cincinnati, in the county of Hamilton and State of Ohio, have invented certain new and useful Improvements in Methods of Cementing the Margins of Flexible Material, of which the following is a specification.

10 The object of my invention is a new and improved method for cementing the margin of flexible material, such for instance as is used in the manufacture of shoe-uppers and other flexible leather, cloth and fabric parts, 15 in the manufacture of shoes, gloves, pocket-books and containers of various kinds, including so-called closed vamps of shoes.

My new and improved method is herein exemplified as accomplished by machinery, 20 but the same may be accomplished by manual means if desired.

The invention consists in the method of moving the margin of the flexible material lengthwise of the margin across a cement- 25 applying part which is moved crosswise of the margin for applying cement to the margin, continuously new surfaces of the margin being presented to the cement-applying part; and further in the method of so relatively moving the margin and cement-applying part mentioned that the cement application is accomplished in lines upon the surface of the margin which are the resultant of the path of movement of the cement- 35 applying part and the cross-line path of movement of the margin of the flexible material.

My invention consists further in the method of applying cement to the margin of 40 flexible material which consists in moving a brush, exemplified as a rotating brush, with its point of cement application moving crosswise of and past the outer edge of the margin which is moving crosswise of the brush, whereby cement strings which may also take the form of a cement film, extend from the margin in adjacency to its outer edge, and laying over these cement strings across the extreme outer edge of the margin, 45 whereby cement application at said extreme outer edge is insured.

My invention consists further in the method of applying cement to the margin of flexible material by applying cement to 50 the margin with a movement crosswise of

the margin and simultaneously feeding the margin of the flexible material lengthwise of the margin crosswise of the cement-applier and laying the cement upon the margin in ridges which extend in directions 60 which are the resultant of the two movements of the cement-applier crosswise of the margin and of the movement of the margin crosswise of the cement-applier; and further in so laying the cement that the ridges 65 are regularly recurrent ridges formed by alternately recurring cement ridges and depressions, so that, when the margin is folded the ridges will be arranged crossingly face to face for insuring good adhesion. 70

My invention consists further in the method of applying cement to the closed margin of a flexible closed vamp whereby the cementation is begun at a given point in the closed margin by a movement of the 75 cement-applier crosswise of the margin and the movement of the margin of the vamp lengthwise of the margin and crosswise of the cement-applier throughout the length of the closed margin and meeting orlapping 80 the point of beginning of cement application to the margin; further in continuously moving the cement-applier past the outer edge of the margin and causing cement-strings to pass said edge and to sever said 85 strings in manner to cause the same to arrange themselves along said outer edge.

In employing my method, further, the closed margin of the closed vamp is moved throughout a closed path corresponding to the closed 90 margin past the cement-applier in such manner that a narrow band of cement is applied to the closed margin in oblique ridges, so that said oblique ridges will meet and be obliquely arranged at the point of 95 beginning and ending of cement application to said closed margin of said closed vamp.

Instrumentalities which may be employed in performing my improved process are exemplified in my applications for patents on 100 improvements in cement applying machines, Serial No. 829,898, filed April 6, 1914, issued as Patent No. 1,154,419, dated September 21, 1915; Serial No. 39,802, filed July 14, 1915; and Serial No. 46,268, filed August 19, 105 1915. The various steps in the method of cement application are shown and described in said applications, but not claimed therein, the claims on the method being part of this application. 110

The margins to be cemented are narrow margins at the edge of the material. When the material is leather these margins are sometimes skived. The margins in the course of manufacture of the article are usually folded and when it is the intention to fold the margin the band of cement is usually approximately twice the width of the fold, so that both the surfaces within the fold shall be cemented prior to the folding, for the reason that the cement employed in this art for the purpose specified has volatile ingredients and adheres best to the surface of the material at its moment of application thereto, the outer surface of the band of cement retaining its tackiness for a period of time after its application to the material, these outer surfaces being placed one upon the other when the fold of the margin is folded upon the body of the margin.

My invention consists further in the method of applying cement to the margin of flexible material in recurrent oblique ridges and progressively folding the margin so cemented with step-by-step or progressive folding movements and arranging the ridges at the sides of the crease of the fold in crossing relation in contact with each other.

The cement usually used in general work of this character has a rubber foundation and is known in the trade as "rubber cement," and this cement used in cementing certain characters of material, for instance, oiled leather or glazed material, further contains an oil-absorbing ingredient, such as chalk or other earthy substance, forming a thicker cement, known in the trade as "white" or "pink" cement, which for convenience will hereinafter be termed "thick cement."

A suitable mechanism which may be employed in performing my improved method, if it is desired to perform the same by mechanism, is exemplified in the accompanying drawings, in which:

Figure 1 is a front elevation of a cement-applying machine, partly broken away, showing the cement being applied to the closed margin of a closed vamp, by my improved method.

Fig. 2 is a vertical section of the cement-applying head of the exemplified device, taken on the line 2—2 of Fig. 3.

Fig. 3 is an end elevation of the device, partly broken away.

Fig. 4 is a cross-section of the cement-applying head taken on the line 4—4 of Fig. 1.

Fig. 5 is a cross-section of the same taken on the line 5—5 of Fig. 1.

Fig. 6 is a cross-section of the same taken on the line 6—6 of Fig. 1.

Fig. 7 is a sectional detail taken on the line 7—7 of Fig. 3, showing the adjusting means for the material support.

Fig. 8 is a longitudinal sectional detail taken on the line 8—8 of Fig. 11, showing the adjusting means for the gage.

Fig. 9 is a cross-sectional detail of the same taken on the line 9—9 of Fig. 8.

Fig. 10 is a front elevation of the cement-applying brush showing its relation to the guide and the cement-control.

Fig. 11 is a rear elevation of the same.

Fig. 12 is a perspective view showing the cement being applied to a margin partly curved convexly and partly straight, viewed from the feeding-out side and away from the operator.

Fig. 13 is a perspective view of the same viewed away from the operator and from the feeding-in side.

Fig. 14 is a perspective view of the same viewed toward the operator and from the feeding-in side.

Fig. 15 is a plan view of the exemplified device, the cement-pot being broken away on the section line 15—15 of Fig. 3.

Fig. 16 is a plan view of a closed vamp laid flat, the closed margin of which is provided with a continuous narrow band of cement by my improved method.

Fig. 17 is an enlarged plan view of a section of a piece of material, represented as a part of the closed vamp, having its margin cemented by my improved method and partly folded, and illustrating the cross relation of the cement-ridges within the fold.

Fig. 18 is a longitudinal section of the same, taken on the line 18—18 of Fig. 17, showing the cement ridges.

Fig. 19 is a cross-section of the same, taken on the line 19—19 of Fig. 17.

Fig. 20 is a side elevation, showing the cement application upon the margin of a piece of material, the material being cut away proximate to the plane of the feeding-out side of the cement-applier; and,

Fig. 21 is a rear elevation of the same.

In the present exemplification, the feeding of the material is accomplished by hand, but, if desired, a power feed may be employed as illustrated, for instance, in my application Serial No. 829,898, filed April 6, 1914, aforesaid.

In my improved method the cement is arranged to be applied to the margin of the flexible material by a suitable cement-applier, exemplified as a rotary cement-applying brush 21, arranged to be rotated in suitable manner. The flexible material is exemplified at *m* in Figs. 12, 13 and 14, as having a margin which is partly convexly curved and partly straight, and at *v* in Figs. 16 to 21 inclusive as a closed vamp. The flexible material is arranged to have its margin 22 provided with a band of cement 23, the margin, in the present exemplification, being manually fed crosswise of the cement-applier.

In order to have a more ready understanding of the method, I shall describe the machine shown in the present exemplification.

5 The frame of the machine is shown as comprising a column 24 extending upwardly from a base 25 arranged to be suitably secured to a suitable support or table 26.

The cement-applying instrumentalities 10 are mounted on a laterally and forwardly extending arm and distanced sufficiently from the column and above the support or table to permit the margins of flexible material of various sizes and shapes, and including closed vamps, to be fed past the cement-applying instrumentalities while stretched or held between the hands of the operator, without interference or contact by said pieces of material or the hands of the 20 operator with the frame of the machine or its table or support.

The arm is shown extending laterally and forwardly from the column by means of a laterally extending portion 27 and forwardly 25 extending portions 28 and 29.

A cement-pot 30 is suitably secured in the forward extension 28 and communicates by a passage 31 with a cement-conveying head 32 in which there is a cement-valve 33. A 30 cement-supplying roller 35 is fast on a shaft 36 journaled in bearings 37 in the head and has a gear 38 fast thereon. It is provided with cement-supplying pockets 39 for conveying the cement to the cement-applying 35 brush, which is exemplified as comprising annular rows of bristles 41 on a bushing 42, the rows of bristles being separated by flat rings 43, for applying alternately heavier and lighter lines of pressure upon the 40 margin. A flange 44 is at one end of the brush. The brush is fixed by means of a set-screw 45 to a sleeve 46 which is received about a shaft 47 and held to the shaft so as to rotate therewith by being provided with 45 an end slot 48 received about a pin 49 in the shaft.

Rotation is imparted to the rotary cement-applying brush by means of a drive-shaft 54 journaled in a bearing 55 on the upper end 50 of the column and a bearing 56 on the outer end of the arm, and provided with a suitable driving means, preferably of such character as to cause rotation and permit cessation of rotation of the rotary cement-applying brush under manual control of the operator during operation of the machine, if this should be desired. The term "manual control" includes any control by the operator during the operation of the machine, 55 whether by hand, foot, knee, or other human control.

I have exemplified these driving means as comprising a pulley 57 arranged for receiving a belt 58 thereabout for rotating the 60 same. The pulley is normally loose on the

shaft. There is a clutch represented as a friction clutch between the pulley and the drive-shaft and arranged, when in clutched relation, to impart motion from the pulley to the drive-shaft, the drive-shaft being non-rotating during unclutched relation of the clutch. The clutch may be of suitable construction and is exemplified as comprising a member 61 fast on the drive-shaft and a member 62 fast on the pulley 57, a friction-band 63 being between said members. A spring 64 normally causes separation of the members 61, 62.

A lever 65 is pivoted upon a bolt 66 on the column and comprises an actuator arm 67, a brake-arm 68, and an operating arm 69. The actuator arm contacts a button 70 of the clutch-member 62 for pushing the clutch-members into clutching relation. The brake-arm has a brake-shoe 71 thereon co-acting with an annular brake surface 72 on the clutch-member 61. The operating arm connects by a connection 73 with a treadle 74 suitably placed on the floor. The lever 65 is normally retracted by a spring 75 connected at one end with the column and at its other end with the operating arm.

When the treadle is depressed by the operator the brake is released and the clutch brought into clutching relation for actuating the drive-shaft and rotating the rotary cement-applying part, and when the treadle is released the clutch is released and the brake applied for causing instant cessation of rotation of the rotary cement-applying 100 part and consequently of cement application, so that rotation of the rotary cement-supplying roller and brush may, under the control of the operator, take place only during the feeding of the material.

The drive-shaft is provided with a gear 76 fast thereon which meshes with an intermediate gear 77 fast on a shaft 78 journaled in a bearing 79 in the forwardly extending portion 29 of the arm of the frame. The gear 77 meshes with a gear 81 on the brush-shaft 47 journaled in a bearing 82 in said forwardly extending portion 29 of the arm. The shaft 78 is also provided with a gear 83 fast thereon which meshes with the gear 38 fast on the shaft 36 to which the cement-supplying roller 35 is secured for rotating the latter, preferably in the direction of the arrow *a*, the rotary cement-applying brush being preferably rotated in the direction of the arrow *b*.

A cement-wiping finger 85 is arranged to contact the side of the flange 44 so as to wipe the cement which may be received on said flange on to the bristles of the brush for keeping the flange clean.

The cement is applied to the margin of the material in the form of the narrow band 23. It is desirable that the margin of the material, during the application of said

70

75

105

110

115

120

125

130

narrow band of cement, be supported and guided, for accomplishing which I exemplify the forwardly extending support 91 located at the side, namely the normal feeding-in side, of the rotary cement-applying brush. This support, which is in the form of a horn, has a gage 92 thereon arranged to be adjusted forward and back on the support for increasing or decreasing the width 10 of the margin presented to the rotary cement-applying part during cement application, and to be clamped in adjusted positions, as by means of a clamp-screw 93 received through a slot 94 in the support and 15 threaded into the gage.

The material supporting face of the material support or horn preferably extends into the longitudinal projection of the periphery of the rotary cement-applying 20 brush, (see Figs. 1, 2, 3, 4 and 6), the said supporting face being preferably a curved face preferably slightly approaching the axis of rotation of the brush at its portion removed from the operator.

25 In order to accommodate different thicknesses of leather having different widths of margins to be cemented and insuring that, especially when the margin is skived, as shown at 95, the thin outer edge thereof has 30 support, the support is arranged to be raised and lowered and held in adjusted positions, as by means of clamp-screws 97 received through a slot 98 in the shank 99 of the support and threaded in threaded apertures of 35 the arm.

The gage is provided with an upwardly curving finger 101, forming a recess 102 having a wide mouth in which the margin of the material is readily received, the said 40 recess preferably contracting toward the gage, against which the outer edge 103 of the margin 22 of the flexible material is arranged to be received when feeding the material past the gage and the rotary cement-applying part. The clearance in the 45 recess is preferably sufficiently high to permit the ready passage of seams therethrough.

In performing my improved method 50 under employment of the exemplified machine, the operator is seated in front of the cement-applying head of the machine, as viewed in Fig. 1, that is, facing the front of the machine marked *f* in Fig. 3. The 55 normal direction of feeding the material is indicated by the arrow *c* in Figs. 12, 13, 14 and 21, the side *d* of the rotary cement-applying part being therefore the normal feeding-in side and the side *e* of said part 60 being the normal feeding-out side thereof.

The gage with its support is located at the feeding-in side of the rotary cement-applying brush and its edge proximate thereto is preferably spaced from the bristles of the 65 brush by a slight space 105, for permitting

the material to be flexed, as shown at 106, about the periphery of the brush, without undue flexure of the bristles of the brush, and for insuring intimate contact between the margin being cemented and the periphery of the brush. This space also permits the ready passage of cross-seams 110 when such are contained in the margin, instanced as the seams of a closed vamp *v*.

In feeding the material manually, it is 75 held by one hand of the operator at the feeding-in side of the rotary cement-applying part, as indicated at 111, and by the other hand of the operator at the feeding-out side of said rotary cement-applying 80 part, as indicated at 112, the margin being supported on the horn and guided by the gage and passed with a quick movement across said gage and the rotary cement-applying part.

The movement of the cement-applying brush in its path crosswise of the margin and the movement of the margin lengthwise of the margin and across the cement-applying brush has the effect of laying the cement 90 in an oblique path or oblique lines, instanced as alternate thicker and thinner lines, forming ridges 114, arranged obliquely across the margin being cemented in a direction which is the resultant of the movement of the 95 cement-applying brush in its path and the feeding movement of the margin, as shown in Figs. 12, 13, 16, 17 and 18.

The movement of the margin crosswise of the brush has a valuable result, in that it 100 avoids the wiping of the cement previously laid on the margin by a previously margin-contacting portion of the brush, a feature especially useful in applying the thick cements hereinbefore referred to, the movement of the brush and material resulting in 105 laying the cement in alternating thicker or thinner lines or ridges, as stated.

The fold of the margin is usually formed with a crease 115 extending lengthwise of 110 the middle of the band of cement. When the fold-portion 116 of the margin is laid upon the body portion 117 of the margin, the lines or ridges of cement at the respective sides of the crease extend in opposite 115 directions and cross relations, so that the uniformly recurrent thick portions of the cement applied will lap each other and cause adhesion between the folded and body portions of the margin when pressed together, 120 as seen more particularly in Fig. 17.

In my improved method the folding is accomplished in step-by-step manner, if desired, for progressively folding and pressing the fold-portion 116 upon the body-portion 125 117, as shown in Figs. 17 and 19, this folding and pressing, in the case of a closed vamp beginning at a suitable point *p*, in the closed margin and continuing throughout said closed margin to the beginning point *p*. 130

The recurrent oblique ridges of the fold-portion 116 are thereby laid and pressed upon the recurrent oblique ridges of the body-portion 117 throughout the closed 5 margin of the closed vamp in crossing relation at the sides of the closed crease of the closed vamp. The closed margin of the closed vamp may be snipped at its concavely curved portions, as shown at 118, accomplished preferably after the cementing has been completed, in advance of the folding, or substantially concurrently therewith, in well-understood manner to permit the proper laying over of the fold-portion at 10 15 said concavely curved portions.

The feeding, folding, pressing and snipping of the margins of flexible material, including the closed margins of closed vamps, may be accomplished if desired by the mechanism shown, described and claimed in my application for patent on folding machines, Serial No. 634,485, filed June 21, 1911.

The degree of pressure of the margin of the material upon the periphery of the brush is readily regulated by the force applied by the hand in stretching the material between the hands at the point of cement application, and also by the direction above or below the plane of the cement-applying 20 25 portion of the brush in which the feeding-out portion of the margin is held.

In employing my method upon a closed vamp, cement application is begun at a given point in the margin thereof, for instance, at the point indicated at *p*, in Figs. 1, 35 16 and 17, the closed margin being moved in the direction of the arrow *c* during movement of the cement-applier crosswise of the margin, and these movements continued 40 until the point of beginning of cement application in the margin is again reached or passed, the margin ends of the seams and stays being also cemented during these movements. The cement is laid in a closed 45 path, and in recurrent oblique ridges as indicated in Figs. 1, 16 and 17, these oblique ridges extending throughout the length of the margin in a closed path of recurrent ridges, the ridges at the beginning and ending of the cementing of the closed path meeting orlapping.

The cross-movement of the brush and lengthwise movement of the margin also results in a "stringing" of cement, as shown 55 at 121, at the feeding-out side of the brush, this stringing sometimes taking the form of a thin film of cement.

This stringing is especially noticeable when the cement-applier is a rotary cement-applying brush, which I have found best for cement-application, as the pressure of the margin upon the bristles and the feeding of the margin lengthwise of the margin and crosswise of the rotating brush causes lateral flexure of the bristles of the brush at

the point of cement-application and a tendency of the cement to follow the feeding movement of the margin, resulting in the stringing mentioned.

The movement of the bristles of the brush in their path is preferably past the outer edge 103 of the margin, but in practice the pressure of the brush upon the margin, whether the brush is a manually manipulated brush or a rotary cement-applying brush, 70 decreases toward the edge of the margin, and in practice it has been found difficult heretofore to apply the cement at the extreme edge of the margin without danger of defacing the face of the leather, it being 75 80 understood that the skived side of the margin is the flesh side of the leather and the finished or face side of the material is the outer surface of the margin.

I have found that by controlling this 85 stringing of the cement I am enabled to lay the cement strings lengthwise upon the extreme outer edge of the margin, whether a convexly or concavely curved or a straight margin, or the closed margin of a closed 90 95 vamp, without danger of defacing the face or opposite side of the material. By pushing or wiping the cement strings toward the outer edge of the margin, closely adjacent to the point of cement application, the strings are cut and the cement, being naturally a somewhat resilient material having rubber as its base, will snap toward the extreme outer edge of the margin at the face thereof being cemented and arrange themselves along said outer edge.

I have found that an interrupting lip adjacent to the brush will accomplish this laying of the cement strings, such a lip being exemplified at 122.

In the present exemplification of mechanism for performing my method the lip 122 is shown as part of a cement-control device 126, which is shown in the form of a plate received about the axis of rotation of the brush. The plate in the form shown is provided with an annular flange 127 at its middle portion which is received about the shaft 47, in the annular recess 128. The plate is held on the shaft by means of a screw 129 which has threaded connection with the end of the brush-shaft.

In order to prevent rotation of the plate with the shaft and brush, it is provided with a tail-piece 130 arranged to contact the cement-applying head, for limiting its rotative movement about the shaft in one direction, but permitting an oscillation of the plate about the shaft, if such should be desired, for instance for cleaning purposes.

The peripheral edge of the cement-control device at that portion thereof proximate to the normal cement-applying portion of the brush and in advance of the material-supporting surface of the material-support,

is located inwardly from the longitudinal projection of the periphery of the rotary cement-applying brush, as shown at 132 so that the bristles of the brush may project beyond said edge.

The lip 122 is shown as comprising a portion 133 which extends at the side of the brush downwardly and outwardly away from the brush, and a portion 134 which 10 extends across the rear edge of the brush, and slopes inwardly, rearwardly and downwardly across the cement-strings 121.

The space between said lip and brush may 15 form a pocket 135 in which the bristles of the brush have lateral flexure during cement application.

The character of the cement employed, which is a tacky, gummy and adhesive substance, and the relative movement between 20 the margin and the brush mentioned, has a tendency, as stated, to cause stringing of the cement between the outer edge of the margin and the periphery of the brush, as seen by the strings 121. These strings of cement 25 normally extend from the margin to the periphery of the brush and would normally follow the periphery of the brush in its rotation, and draw the cement away from the outer edge of the material.

30 I have found for instance where the relative movements between the margin and brush results in a recession of the outer edge of the margin away from the brush, exemplified in Figs. 12, 13 and 14, by a movement 35 of the convexly curved portion 136 of the margin away from the brush and toward the operator, the strings have a tendency to pull the cement away from the outer edge of the margin being cemented and thereby leave 40 this outer edge of the margin uncemented. In order to prevent this undesirable condition, I have provided the lip 122.

The movement of the bristles of the brush 45 at the pocket 135, causes the brush in its rotation to carry with it any excess accumulation of cement in the pocket back to the in-feeding portion of the cement-supplying roller.

The lower edge of the cement control lip 50 slopes toward the outer edge of the margin being cemented, when in cement-applying position, and is arranged to contact the strings of cement extending from the margin, and lay them upon the outer edge 103 55 of the margin, and cut said strings, the cut brush-end portions of the strings following the periphery of the brush to the cement-supplying roller, and the cut portions of the cement-strings at the outer edge of the margin being laid upon said outer edge, so as to 60 insure cement application throughout the margin at the extreme outer edge thereof, as exemplified in Figs. 12, 13, 14, 20 and 21.

Having thus fully described my invention,

what I claim as new and desire to secure by 65 Letters Patent is:

1. The method of cementing the margin of flexible material which consists in moving the margin of the flexible material lengthwise of said margin across a cement-applying 70 part which is moved across and toward the outer edge of the lengthwise moving margin for applying cement thereto throughout the application of cement to said margin.

2. The method of cementing the margin 75 of flexible material which consists in moving the margin of flexible material lengthwise of said margin across a cement-applying part which is moved across and toward the outer edge of the lengthwise moving margin for 80 applying cement thereto in paths oblique to the edge of said margin which are the resultants of said movements of said margin and said cement-applying part throughout the application of cement to said margin. 85

3. The method of cementing the margin of flexible material which consists in moving the margin of flexible material lengthwise of said margin across a cement-applying part which is moved crosswise of the 90 lengthwise moving margin and applying cement thereto in oblique ridges which are the resultant of said movements of said margin and said cement-applying part.

4. The method of cementing and folding 95 the margin of flexible material which consists in moving the margin of flexible material lengthwise of said margin across a cement-applying part which is moved crosswise of said lengthwise moving margin and applying cement thereto in oblique ridges which are the resultant of said movements of said margin and said cement-applying part, and folding said margin with a crease intermediate of its width and crossingly arranging said ridges at the sides of said crease in 100 contact with each other. 105

5. The method of cementing the margin of flexible material which consists in moving the margin of the flexible material 110 lengthwise of said margin across a cement-applying part which is moved crosswise of the lengthwise moving margin and past the outer edge thereof for applying cement to said margin and causing cement to extend 115 from said outer edge, and laying said extending cement lengthwise of said outer edge.

6. The method of cementing the margin of flexible material which consists in moving the margin of flexible material lengthwise of said margin across a cement-applying part which is moved crosswise of the lengthwise moving margin and past the outer edge thereof for applying cement to 120 said margin in oblique paths crosswise of said margin which are the resultant of said movements of said margin and said cement- 125

applying part and causing cement to extend from said outer edge, and laying said last-named cement on said outer edge.

7. The method of cementing the margin 5 of flexible material which consists in moving the margin of flexible material lengthwise of said margin across a cement-applying part which is moving crosswise of the lengthwise moving margin and past the 10 outer edge thereof and applying alternately heavier and lighter lines of pressure upon said margin for applying cement to the margin in oblique ridges which are the resultant of said movements of said margin 15 and said cement applying part and causing cement-strings to extend from said outer edge, and laying said cement-strings on said outer edge.

8. The method of cementing the margin 20 of flexible material which consists in moving the margin of flexible material lengthwise of said margin across a cement-applying part which is moved across and toward the outer edge of the lengthwise moving 25 margin and manually moving said margin into selective elevations about said cement-applying part with relation to the cement-applying portion of said cement-applying part.

30 9. The method of applying cement to the margin of flexible material which consists in moving the margin lengthwise of said margin across a cement-applying part which is moved crosswise of the lengthwise moving 35 margin and past the outer edge thereof for applying cement to said margin and causing cement-strings to extend from said outer edge, laying said cement-strings along said outer edge, and manually guiding said margin to elevation with relation to said cement-applying part for controlling said laying.

10. The method of cementing the margin 40 of flexible material which consists in moving the margin of flexible material lengthwise of said margin across a cement-applying part which is moved crosswise of the lengthwise moving margin for applying cement thereto, and controlling said cement- 45 applying by manual manipulation of said margin.

11. The method of cementing the margin 50 of a closed vamp of flexible material which consists in moving said margin lengthwise of said margin across a cement-applying part moving in a direction crosswise of the direction of movement of said margin across said margin and toward its outer edge throughout the application of cement to said 55 margin.

12. The method of applying cement to the margin of flexible material which consists in moving said margin past a cement-applying part moving in a direction crosswise of the 60

direction of movement of said margin while 65 in contact with said cement-applying part in such manner that obliquely arranged ridges of cement are applied to said margin so that when the fold of said margin is folded back upon the body of said margin 70 the said obliquely arranged ridges on said fold and body are arranged in crossing relations and in contact with each other.

13. The method of cementing and folding the margin of flexible material which consists in applying a narrow band of cement 75 in oblique lines to the margin to be folded in a direction toward the outer edge of said margin and then folding the fold of said margin upon the body of said margin whereby said oblique lines of cement at the respective sides of said band are arranged in crossing relation in contact with each other.

14. The method of cementing and folding the margin of flexible material which consists in applying a narrow band of cement 80 of substantially twice the width of the fold of said margin in oblique lines to the margin to be folded in a direction toward the outer edge of said margin, forming a crease 90 in said margin lengthwise thereof and at substantially its middle and folding the fold of said margin upon the body of said margin whereby said oblique lines of cement at 95 opposite sides of said crease are arranged in crossing relation in contact with each other.

15. The method of cementing and folding the margin of flexible material which consists in applying a narrow band of cement 100 of substantially twice the width of the fold of said margin in oblique lines to the margin to be folded in a direction toward the outer edge of said margin, forming a crease in said margin lengthwise thereof and at substantially its middle and folding the fold 105 of said margin upon the body of said margin whereby said oblique lines of cement at opposite sides of said crease are arranged in crossing relation in contact with each other, then pressing said fold and body of said 110 margin together.

16. The method of cementing the closed margin of a closed vamp of flexible material which consists in moving said closed margin from a given point therein lengthwise of said margin across a cement-applying part which is moved across the lengthwise moving margin, toward the outer edge of said margin, for applying a band of cement thereto which substantially meets at said given point therein.

17. The method of cementing the closed margin of a closed vamp of flexible material which consists in moving said closed margin from a given point therein lengthwise of said closed margin across a cement-applying part which is moved crosswise of the lengthwise moving margin and past the 125

outer edge thereof for applying a band of cement to said margin and causing cement-strings to extend from said outer edge and laying said cement-strings as formed upon 5 said outer edge and substantially closing said band by said movements.

18. The method of cementing the closed margin of a closed vamp of flexible material which consists in moving said closed 10 margin from a given point therein lengthwise of said margin across a cement-applying part which is moved crosswise of the lengthwise moving margin and applying cement thereto in oblique ridges which 15 are the resultant of said movements of said closed margin and said cement-applying part and continuing said movements substantially throughout said closed margin and thereby applying a narrow band of 20 recurrent oblique ridges of cement substantially throughout said closed margin.

19. The method of cementing and folding the closed margin of a closed vamp of flexible material which consists in moving said closed 25 margin from a given point therein lengthwise of said margin across a cement-applying part which is moved crosswise of the lengthwise moving margin and applying cement thereto in oblique ridges which 30 are the resultant of said movements of said closed margin and said cement-applying part and continuing said movements substantially throughout said closed margin and thereby applying a narrow band of 35 recurrent oblique ridges of cement substantially throughout said closed margin, and folding said closed margin with a crease intermediate of its width and crossingly arranging said ridges at the sides of said 40 crease in contact with each other.

20. The method of cementing and folding the closed margin of a closed vamp of flexi-

ble material which consists in moving said closed margin from a given point therein lengthwise of said margin across a cement-applying part which is moved crosswise of the lengthwise moving margin and applying cement thereto in oblique ridges which 45 are the resultant of said movements of said closed margin and said cement-applying part and thereby applying a narrow band of recurrent oblique ridges of cement substantially throughout said closed margin, and folding the outer portion of said closed margin upon the inner portion of said closed margin with recurrent step-by-step 50 folding movements continuing progressively from a given point in said margin substantially throughout said closed margin with a crease extending lengthwise of said margin intermediate of the width of said margin and crossingly arranging said ridges 55 at the sides of said crease in contact with each other.

21. The method of cementing the closed margin of a closed vamp of flexible material which consists in moving said closed margin from a given point therein lengthwise of said margin across a cement-applying part which is moved across the 60 lengthwise moving margin toward the outer edge of said margin, while the depending portion of said closed vamp is hanging free of dragging contact for applying a band of cement to said closed margin which substantially meets at said given point.

In testimony whereof, I have hereunto subscribed my name in the presence of two subscribing witnesses.

WILLIAM F. LAUTENSCHLAGER.

Witnesses:

THERESA M. SILBER,
CHARLES E. WEBER.
